UNITED STATES PATENT OFFICE.

CHARLES R. WITTEMANN AND ADOLPH D. WITTEMANN, OF NEW YORK, N. Y.

FLYING-MACHINE.

1,077,111.

Specification of Letters Patent.

Patented Oct. 28, 1913.

Application filed April 18, 1910. Serial No. 555,990.

To all whom it may concern:

Be it known that we, CHARLES R. WITTEMANN and ADOLPH D. WITTEMANN, citizens of the United States, residing at the city of New York, borough of Richmond, Richmond county, in the State of New York, have invented certain new and useful Improvements in Flying-Machines, of which the following is a full, clear, and exact

specification.

Our invention relates to that class of flying machines generally known as the "heavier-than-air" type, and the same has for its object more particularly to provide a simple, efficient apparatus which is easy to operate, and to maintain properly balanced while in operation.

Further, said invention has for its object to provide a flying machine of light construction, having its parts so arranged and braced as to make the same strong and durable.

Further, said invention has for its object to provide a flying machine, comprising a plurality of separate or independent planes arranged substantially in the same horizontal plane.

Further, said invention has for its object to provide a flying machine having its parts so arranged that the machine as a whole lies within the geometrical outline of a circle.

Further, said invention has for its object to provide a flying machine having a plurality of separate vanes for stabilizing the apparatus.

To the attainment of the aforesaid objects and ends, our invention consists in the novel details of construction, and in the combination, connection and arrangement of parts hereinafter more fully described and then pointed out in the claims.

In the accompanying drawings forming part of this specification wherein like numerals of reference indicate like parts, Figure 1 is a perspective view, showing one form of flying machine constructed according to and embodying our said invention; Fig. 2 is a top view thereof; Fig. 3 is a longitudinal section taken on the line 3—3 of Fig. 2; Fig. 4 is a diagrammatic perspective view of the steering rudder, and the means for operating the same; Fig. 5 is a diagrammatic perspective view, showing the balancing vanes, and the means for operating the same; Figs. 6 and 7 are respectively face and top views of one of the

balancing vanes, and Fig. 8 is a detail inverted plan view, showing the construction of the rear plane.

In said drawings, 10 designates the flying machine as a whole, composed of two main or longitudinal struts 11, 12, which are secured about midway of their ends to a pair of forward struts 13, 13, and a pair of rear struts 13^a, 13^a. The main or longitudinal struts 11, 12, are secured to the vertical struts or supports about midway between the ends of said vertical struts or supports, and said main or longitudinal struts 11, 12, are maintained parallel and duly separated from each other by means of a long forward transverse strut 14, and a shorter transverse strut 15. The forward transverse strut 14 is secured and supported upon the front edges of the forward vertical struts 13, 13, and bearing upon the upper surfaces of the main or longitudinal struts 11, 12, while the rear transverse strut 15 is secured to the rear vertical struts 13^a, 13^a, and the upper surfaces of the main or longitudinal struts 11, 12. Each pair of vertical struts 13, 13^a, are secured together at their upper and lower ends by short longitudinal guys 16, 16, and the ends of each pair of vertical struts 13, 13, and 13^a, 13^a, are secured together by transverse guys 17, 17.

18, 18 denote diagonal guys connecting the upper and lower ends of the two forward vertical struts 13, 13, and the similar ends of the two rear vertical struts 13^a, 13^a, 19, 19, denote diagonal guys connecting the upper and lower ends of each pair of vertical struts 13, 13^a.

The forward ends of the main or longitudinal struts 11, 12, are connected by guys 20, 20, with the upper ends of the forward vertical struts 13, 13, and to the lower ends thereof by guys 21, 21, while the rear ends of said main or longitudinal struts 11, 12, are connected to the corresponding ends of the rear vertical struts 13^a, 13^a, by guys 20^a, 20^a, and 21^a, 21^a. The portions of the main or longitudinal struts intermediate the forward vertical struts 13, 13, and the ends of said main or longitudinal struts are connected to the upper and lower ends of the forward vertical struts 13, 13, by transverse guys 21, 21, 22, 22, and the corresponding rear portions of the main or longitudinal struts 11, 12, are connected to the corresponding ends of the rear vertical struts 13^a, 13^a, by means of short guys 21^a, 22^a. Adjacent

cent to the lower ends of the forward vertical struts 13, 13, and the rear vertical struts 13^a, 13^a, are secured transverse members or braces 23, 23^a, and centrally upon 5 said transverse members or braces 23, 23^a, are arranged two longitudinal supporting members 24, 24, which are arranged side by side, and serve as the support for the motor 25, and the seat 26 for the aviator.

10 The rear struts 13^a, 13^a, extend a short distance below the lower ends of the forward vertical struts 13, 13, and are provided with wheels 27, 27. From the forward transverse strut 14 extends downwardly and forwardly a forked rod 28, within the lower or forked end of which is mounted a wheel 29. The end of said fork is braced by two diagonal members 30, 30, extending from said fork to the main or longitudinal struts 11, 12, adjacent to the forward vertical struts 13, 13, and members 31, 31, extending from the lower ends of said diagonal members 30, 30, to the main or longitudinal struts 11, 12, adjacent to the forward ends of the short 20 guys 21, 21. The forward and rear ends of the main or longitudinal struts 11, 12, are secured together by two transverse members 32, 32^a. The members 32, 32, being secured upon the upper surfaces of the main or longitudinal struts 11, 12, and the members 32^a, 32^a, being secured to the under surfaces of said struts 11, 12, and 33, 33 denote a series 30 of curved ribs arranged longitudinally of the frame, which are secured at their forward ends to the upper surfaces of the transverse members 32, 32, and adjacent to their rear ends to the upper surfaces of the transverse members 32^a, 32^a, which curved ribs together with the transverse members 32, 32^a, constitute the framework upon which the fabric covers 34, 34 are secured to form the forward and rear planes.

Upon the rear plane is mounted a steering rudder 35 provided at its upper and lower 45 ends with pivot pins 36, 36, the lower of which is socketed in the transverse member 32, while the upper pivot pin 36 is disposed in an eye 37 secured in position by four transverse guys 38, 38, having their lower 50 ends secured to the main or longitudinal struts 11, 12.

39, 39 denote flexible connections or ropes extending from the rear edge of the steering rudder to an operating lever 40 secured 55 upon the transverse brace 23. Upon the transverse member 32 secured to the forward ends of the main or longitudinal struts 11, 12, are arranged two upwardly projecting supports 41, 41, between which is pivotally mounted an elevating plane 42, provided with an arm 43 at its forward edge, to the ends of which are connected the ends of flexible connections 44, 44, having their rear ends secured to an operating lever 45 65 pivotally mounted upon the longitudinal

member 24 secured to the transverse members 23, 23. The vertical supports 41, 41, are secured in position by diagonal guys 46, 46.

To each of the main or longitudinal struts 11, 12, are secured transverse members 47, 47, which are arranged to the rear of the forward transverse member 14, and connected thereto by a plurality of curved longitudinal ribs 48, 48. The transverse member 14 together with the shorter transverse members 47, 47, and the longitudinal ribs 48, 48, connecting the same, serve to form frames at each side of the main or longitudinal struts for the coverings 49, 49. The said coverings together with their frames constitute substantially flat planes arranged at either side of the main or longitudinal struts 11, 12, midway between the forward and rear planes 34, 34.

48^a, 48^a, denote horizontal guys or stays connecting the forward ends of the main or longitudinal struts 11, 12, with the ends of the transverse strut 14, and 48^b, 48^b, denote similar guys or stays connecting the rear ends of said main or longitudinal struts 11, 12, with the shorter transverse members 47, 47, of the side planes 49, 49. Upon each of the side planes 49, 49, are arranged vertical supports 50, 50, which have their lower ends secured to the transverse members 14 and 47. Within said vertical supports 50, 50, are pivotally mounted balancing vanes 51, 51, having their lower edges inclined rearwardly and downwardly, and their upper rear edges or ends bent upwardly and forwardly. The said balancing vanes 51, 51, are connected together at their upper forward and lower rear ends by flexible connections 52, 52, and from the forward pivoted ends of said balancing vanes 51, 51, extend downwardly arms 53, 53, to which are secured the ends of flexible members or ropes 54, 54, which are brought together and secured to an operating lever 55, arranged upon the transverse brace 23.

The general operation of the apparatus is obvious. In order to maintain the machine properly balanced when in flight, it merely becomes necessary to shift the balancing vanes 51, 51, by means of the operating lever 55, which is connected to said balancing vanes by the flexible connection 52, and adjust said balancing vanes to the required angle. By shifting the operating lever 55, to the right or left as the case may be, the upper curved edge of the righthand balancing vane will be moved outwardly and downwardly, while the corresponding end of the lefthand balancing vane will be moved inwardly. By this movement a greater portion of the outer surface of the righthand balancing vane 51 will be caused to assume a more horizontal position and thereby offer a greater 130

resistance to the air and serve to lift the righthand plane 49, the lefthand balancing plane 41 at the same time being caused to present a smaller area to the air and lessening the resistance of the air thereto will permit of the lefthand plane 49 rising and thus cause the machine as a whole to move and become properly balanced and maintain the same in that position.

10 It will be noted that the balancing vanes 51, 51, are equally well adapted for use in connection with biplane as well as monoplane machines, regardless of the fact whether the same be positively propelled by 15 a motor, or operated by force of gravity. Further, it will be noted that the balancing vanes 51, 51, automatically serve to maintain the machine properly balanced while in flight, and that any number of the same 20 may be used, whether stationary or adjustable, and disposed upon any part or parts of the machine above the planes 34, 34, and 49, 49.

Having thus described our invention, 25 what we claim and desire to secure by Letters Patent is:

1. A flying machine comprising a cruciform frame having planes at its ends, means for propelling said machine, a steering rudder, an elevating plane, and a plurality of balancing vanes arranged in vertical positions parallel to the direction of travel upon said frame and having their upper rear ends turned outwardly and forwardly, substantially as specified.

2. A flying machine comprising a cruciform frame having substantially flat planes at its several ends, means for propelling said machine, a steering rudder, an elevating plane, and a plurality of automatically operating pivoted balancing vanes arranged vertically lengthwise of said frame, and having end portions turned outwardly and forwardly, substantially as specified.

3. A flying machine comprising a cruciform frame having substantially flat planes at its several ends, a motor for propelling said machine, a steering rudder, an elevating plane, and a plurality of automatically operating vertical balancing vanes arranged upon said frame, having outwardly extending portions at their rear upper ends, substantially as specified.

4. A flying machine comprising a cruciform frame having substantially flat planes at its several ends, a motor for propelling said machine, a steering rudder, a plurality of vertical balancing vanes arranged upon opposite sides of said frame having their upper rear ends curved outwardly and forwardly, and means for adjusting said balancing vanes, substantially as specified.

5. A flying machine comprising a main frame and side frame members extending laterally therefrom, planes arranged at the

ends of said main frame and side frame members, means for propelling said machine, steering and elevating means, and a plurality of vertical balancing vanes pivotally mounted and arranged parallel to the direction of travel of said machine, and each having one of its rear corners bent outwardly and forwardly, substantially as specified.

6. A flying machine comprising a main frame and side frame members extending laterally therefrom, planes arranged at the ends of said main frame and side frame members, means for propelling said machine, steering and elevating means, and a plurality of connected vertical balancing vanes arranged vertically and parallel to the direction of travel of said machine, and having their rear corners extending outwardly and forwardly, substantially as specified.

7. A flying machine comprising a main frame and side frame members extending laterally therefrom, planes arranged at the ends of said main frame and side frame members, means for propelling said machine, steering and elevating means, and a plurality of connected balancing vanes mounted adjacent to the outer ends of said side frame members and arranged vertically parallel to the direction of travel of said machine, and having their upper rear ends extending outwardly and forwardly, substantially as specified.

8. A flying machine comprising a main frame and side frame members extending laterally therefrom, planes arranged at the ends of said main frame and side frame members, means for operating said machine, a plurality of pivotally supported balancing vanes arranged vertically upon said frame and parallel to the longitudinal axis of said main frame, and having their rear corners extending outwardly and forwardly, and means for adjusting said balancing vanes transversely to the direction of travel of said machine, substantially as specified.

9. A flying machine comprising a main frame and side frame members extending laterally therefrom, planes arranged at the ends of said main frame and side frame members, means for operating said machine, a plurality of pivotally-supported balancing vanes having their rear ends bent diagonally outward and forward; said balancing vanes being connected together and arranged vertically upon opposite sides of said frame, and parallel to the direction of travel of said machine, and means for simultaneously adjusting said balancing vanes, substantially as specified.

10. A flying machine comprising a main frame and side frame members extending laterally therefrom, planes arranged at the ends of said main frame and side frame

members, means for operating said machine, and a plurality of pivoted vertical balancing vanes arranged vertically and parallel with the direction of travel of said machine, and 5 having their upper ends curved outwardly, substantially as specified.

11. A flying machine comprising a main frame and side frame members extending laterally therefrom, planes arranged at the 10 ends of said main frame and side frame members, means for operating said machine, and a plurality of pivoted vertical balancing vanes having their upper rear ends bent outwardly and forwardly, substantially as 18 specified.

12. A flying machine comprising a main frame and side frame members extending laterally therefrom, planes arranged at the 20 ends of said main frame and side frame members, means for operating said machine, supports arranged upon each side frame, and a plurality of balancing vanes having their rear ends bent diagonally outward and forward; said 25 balancing vanes being vertically pivotally mounted in said supports, and arranged parallel to the direction of travel of said machine, substantially as specified.

13. A flying machine comprising a main 30 frame and side frame members extending laterally therefrom, planes arranged at the ends of said main frame and side frame members, means for operating said machine, supports arranged upon each side frame, a 35 plurality of balancing vanes pivotally mounted vertically lengthwise in said supports, and having their rear ends bent diagonally outward and forward; said balancing vanes being arranged parallel to the 40 direction of travel of said machine, and means for adjusting said balancing vanes, substantially as specified.

14. A flying machine comprising a main frame and side frame members extending 45 laterally therefrom, planes arranged at the ends of said main frame and side frame members, means for operating said machine, supports arranged upon opposite sides of 50 said frame and extending upwardly therefrom, a plurality of balancing vanes pivotally mounted vertically lengthwise in said supports, and having their rear ends bent diagonally outward and forward; said balancing vanes being arranged parallel to the 55 direction of travel of said machine, and means for adjusting said balancing vanes, substantially as specified.

15. A flying machine comprising a main frame and side frame members extending 60 laterally therefrom, planes arranged at the ends of said main frame and said side frame members, means for operating said machine, supports arranged upon said side frame members and extending upwardly 65 therefrom, balancing vanes having their

rear upper ends bent diagonally outward and forward, and said balancing vanes pivotally mounted vertically lengthwise in said supports and parallel to the direction of travel of said machine, means connecting 70 said balancing vanes, and means for simultaneously adjusting said balancing vanes transversely to the direction of travel of said machine, substantially as specified.

16. A flying machine comprising a main frame and side frame members extending laterally therefrom, planes arranged at the 75 ends of said main frame and side frame members, means for operating said machine, supports arranged upon said side frame members adjacent to the ends thereof and extending upwardly therefrom, balancing vanes having their rear upper ends bent diagonally outward and forward, and said 80 balancing vanes pivotally mounted vertically lengthwise in said supports, and arranged parallel to the direction of travel of said machine, means connecting said balancing vanes, and levers for simultaneously 85 adjusting said balancing vanes transversely to the direction of travel of said machine, substantially as specified.

17. A flying machine comprising a frame, sustaining planes thereon, means for propelling said machine, a steering rudder, an 90 elevating plane, and a plurality of pivoted balancing vanes carried by said frame in vertical positions parallel to the direction of travel of said machine, and having their upper rear ends turned outwardly and forwardly, substantially as specified. 100

18. A flying machine comprising a frame, sustaining planes carried thereby, means for propelling said machine, a steering rudder, an elevating plane, and a plurality of balancing vanes carried by said frame in vertical positions parallel to the direction of travel of said machine, and having their rear upper ends adjusted to project diagonally outward and forward therefrom, 110 substantially as specified. 105

19. A flying machine comprising a cruciform frame, having planes of substantially equal area arranged at the ends thereof, and said planes having their forward and rear edges parallel and arranged respectively in the same horizontal planes, means for operating said machine, and a plurality of balancing vanes having their upper rear ends bent diagonally upward and forward, 115 said balancing vanes being mounted upon said frame at the opposite ends thereof, and pivotally supported vertically lengthwise upon said frame, and parallel to the direction of travel of said machine, substantially 120 as specified. 125

20. A flying machine comprising a cruciform frame composed of a pair of forward vertical struts and a pair of rear vertical struts, a pair of separated horizontal longi- 130

tudinal struts secured to said forward and rear vertical struts, a forward transverse strut secured to said forward vertical struts and said horizontal longitudinal struts, a 5 shorter transverse strut secured to the rear vertical struts, and to said longitudinal horizontal struts, transverse struts secured to said vertical struts adjacent to their lower ends, longitudinal members mounted 10 upon said lower transverse struts, means for operating the machine mounted upon said longitudinal members, guys uniting said vertical struts together and said longitudinal and transverse struts together 15 and to the ends of said vertical struts, planes secured at the ends of said longitudinal and transverse struts, a steering rudder pivot-

ally mounted upon said rear plane, means for operating said rudder, an elevating plane mounted upon said forward plane, 20 means for operating said elevating plane, balancing vanes pivotally supported upon the frame to each side of said horizontal longitudinal struts, and means for simultaneously adjusting said balancing vanes, 25 substantially as specified.

Signed at the city of New York, county of New York, in the State of New York, this 30th day of March, 1910.
